FIG. 6

UNITED STATES PATENT OFFICE.

JOSEPH E. B. DANIEL AND EDWARD LOUTHAN, OF LOS ANGELES, CALIFORNIA, AS
SIGNORS TO WESTERN BLIND & SCREEN COMPANY, OF LOS ANGELES, CALIFORNIA.

TILTING-MEMBER ASSEMBLY FOR VENETIAN BLINDS.

Application filed February 9, 1928. Serial No. 253,005.

This invention relates to an improved tilting member assembly for Venetian blinds, and has for one of its principal objects the provision of means for the secure support 5 of a Venetian blind, while at the same time allowing of ease and simplicity of operation.

One of the important objects of this invention is to provide, in a Venetian blind, a tilting member assembly, comprising the top 10 tilting bar of such a blind, which in turn supports the blind itself, and a pivotal or tilting support for this bar which will insure easy action of the tilting function and free running of the operating cords.

15 Another and still further important object of the invention is to provide, in a tilting member assembly for Venetian blinds, means for supporting the blind itself in position for easy tilting without the use of ball 20 or cone bearings, and with the avoidance of obstructive binding or undue slackness, while at the same time affording a noiseless action.

Other and further important objects of the 25 invention will be apparent from the disclosures in the accompanying drawings and following specification.

The invention, in a preferred form, is illustrated in the drawings and hereinafter more 30 fully described.

In the drawings:

Figure 1 is an end view of the improved tilting member assembly of this invention, showing the top portion of a Venetian blind 35 supported thereby.

Figure 2 is a detail view illustrating the action of the tilting drum.

Figure 3 is a front view of the upper left hand corner of the blind, illustrating the 40 parts shown in Figure 1.

Figure 4 is a sectional view taken through the middle of the friction drum, showing the details thereof.

Figure 5 is a detail view of the square shaft 45 which supports the tilting bar of the blind.

Figure 6 is a detail view of the friction washer used on the shaft.

As shown in the drawings:

The reference numeral 10 indicates generally the fixed supporting bar of a Venetian

blind adapted to be fastened in position by means of brackets or the like 12. Fastened to the under side of one end of the bar 10, and depending therefrom, is a support for the tilting bar 14 of the Venetian blind, which 55 support comprises a plate formed integrally in four main parts 16, 18, 20, and 22, each of these parts comprising a somewhat circular portion of the plate, the portions 16 and 18 being of considerably larger diameter than 60 the portions 20 and 22. The portions 16 and 18 and 20 and 22 are, respectively, opposite each other and form bearing plates for a rotatable supporting of a friction drum 24 and a pulley wheel 26, as best shown in Figures 65 2 and 3.

The pulley wheel 26 is mounted on a pin or axle 28, which is fitted into suitable openings in the circular portions 20 and 22 of the supporting plate, thereby allowing of free 70 rotation of this pulley wheel and a suitable action of the operating cords 30 which are trained over this wheel.

The friction drum 24 is mounted between the circular plate members 16 and 18 in such 75 a fashion as to eliminate any actual axle support for the drum itself, the rear face of the drum being formed with an integral circular struck out projection 32 which fits into the corresponding opening formed in the rear 80 face of the plate 18, and the front face of the drum 24 is cut away to form four radially extending lugs 34 which in turn are bent slightly outwardly all along their path from the circumference to the center of the drum 85 and at their ends are formed with a more decided outward turn, as shown at 36 in Figure 4.

The ends 36 of these radial members 34 are then fitted into a corresponding circular opening formed in the outer face 16 of the supporting plate, thereby allowing of a free rotation of the friction drum 24 in its support, while at the same time insuring noiseless operation and preventing any looseness or 95 tendency to rattle.

Fitted into the end of the tilting bar 14 is a square shaft 40, which extends outwardly through the friction drum 24 and the supporting plates 16 and 18, and has screw 100

threaded ends, as shown at 42 for the reception of a securing nut 44.

A journal washer 46 is positioned behind the nut 44 so as to retain the shaft in proper relation to the drum and the bearing plates at all times.

Adjustment of the nut 44 will regulate the frictional relation between the drum and the supporting plates.

10 A friction washer 48 is provided between the inner face of the plate 18 and the outer end of the tilting member 14, which itself is guarded by means of a metal plate or the like 50 fastened in position by means of nails 15 or rivets 52.

An opening 60 is formed in the periphery of the drum 24 and into this opening is placed the knotted ends of the operating cords 30 which pass around the drum in any suitable 20 manner, preferably, as indicated in Figure 2, so as to allow of a ready turning of the drum, which will accordingly move the square shaft 40 with it, the shaft 40 being fitted into a corresponding square opening in the rear 25 face 32 of the drum 24. Tilting of the member 14 acts to tilt all of the slats 54 of the blind in the usual manner.

It will be seen that herein is provided a 30 tilting member assembly for Venetian blinds which is simple and noiseless in operation, and which will effectively produce the desired operation of a Venetian blind with a minimum expenditure of labor and inconvenience.

35 The construction of the drum allows of the use of a single operating cord, the ends of which are knotted and positioned inside the drum by passing the middle doubled end of the cord through the openings between the 40 radial members 34 and thence outwardly through the opening 60, thereby providing a very neat appearing construction.

The other end of the tilting bar is provided with the usual pin, and is supported in an 45 end bracket, which may be of any desired construction.

We are aware that many changes may be made and numerous details of construction varied throughout a wide range without departing from the principles of this invention, and we therefore do not purpose limiting the 50 patent granted hereon otherwise than as necessitated by the prior art.

We claim as our invention:

55 1. A tilting member assembly for Venetian blinds, including supports for the top member of the blind, one of said supports comprising a rotatable drum, bearing plates for the drum, and a shaft in the end of the 60 top bar of the blind passing through said drum.

2. A tilting member assembly for Venetian blinds, including supports for the top member of the blind, one of said supports comprising a rotatable drum, bearing plates for the 65

the drum, and a square shaft in the end of the top bar of the blind passing through said drum, and rotatable therewith.

3. A tilting member assembly for Venetian blinds, including supports for the top member of the blind, one of said supports comprising a rotatable drum, bearing plates for the drum, and a shaft in the end of the top bar of the blind passing through said drum, and friction bearings between the 75 drum and the supporting plates.

4. A tilting member assembly for Venetian blinds, including supports for the top member of the blind, one of said supports comprising a rotatable drum, bearing plates for the drum, and a shaft in the end of the top bar of the blind passing through said drum, and friction bearings between the drum and the supporting plates, said friction bearings comprising radial lugs on one face of the 85 drum normally bent slightly outwardly.

5. A tilting member assembly for Venetian blinds, including supports for the top member of the blind, one of said supports comprising a rotatable drum, bearing plates for the drum, and a shaft in the end of the top bar of the blind passing through said drum, and friction bearings between the drum and the supporting plates, said friction bearings comprising radial lugs on one face of the 95 drum normally bent slightly outwardly, and with their ends turned additionally outwardly to contact with the inner edges of a circular opening in the supporting plate.

6. A tilting member assembly for Venetian blinds, including supports for the top member of the blind, one of said supports comprising a rotatable drum, bearing plates for the drum, and a shaft in the end of the top bar of the blind passing through said drum, and friction bearings between the drum and the supporting plates, said friction bearings comprising radial lugs on one face of the 100 drum normally bent slightly outwardly, and with their ends turned additionally outwardly to contact with the inner edges of a circular opening in the supporting plate, together with an outwardly struck circular portion in the other face of the drum adapted to contact with a similar circular opening in its respective supporting plate.

7. A tilting member assembly for Venetian blinds, comprising a square shaft in the end of the top tilting bar of the blind, a friction drum mounted on said shaft and rotatable therewith, and bearing plates for the drum, together with a nut and a friction washer on the shaft for maintaining the drum in desired operative relation with the bearing plates.

8. A tilting member assembly for Venetian blinds, comprising a square shaft in the end of the top tilting bar of the blind, a friction drum mounted on said shaft and rotatable therewith, and bearing plates for the drum, together with a nut and a friction 125

washer on the shaft for maintaining the drum in desired operative relation with the bearing plates and for adjusting the amount of friction between the drum and the said 5 plates.

9. A tilting member assembly for Venetian blinds, comprising a square shaft in the end of the top tilting bar of the blind, a friction drum mounted on said shaft and rotatable therewith, and bearing plates for the drum, together with a nut and a friction washer on the shaft for maintaining the drum in desired operative relation with the bearing plates and for adjusting the amount of friction between the drum and the said plates, together with an operating cord having both of its ends knotted and positioned inside the drum.

10. A tilting member assembly for Venetian blinds, comprising a square shaft in the end of the top tilting bar of the blind, a friction drum mounted on said shaft and rotatable therewith, and bearing plates for the drum, together with a nut and a friction washer on the shaft for maintaining the drum in desired operative relation with the bearing plates and for adjusting the amount of friction between the drum and the said plates, together with an operating cord having both of its ends knotted and positioned inside the drum, and an operating pulley for the cords, said pulley being supported in bearing plates integral with the bearing plates for the drum.

In testimony whereof we affix our signatures.

JOSEPH E. B. DANIEL
EDWARD LOUTHAN.
